United States Patent Office

Des. 197,988
Patented Apr. 14, 1964

197,988

BOX

Leo R. Slaton, Chicago, Ill., assignor to Swiss Harmony,
Inc., Chicago, Ill., a corporation of Illinois

Filed May 9, 1963, Ser. No. 74,825

Term of patent 7 years

(Cl. D58—12.6)

FIG. 1 is a perspective view of a box embodying my new design, and

FIG. 2 is an end elevation view thereof.

The back and end not shown in the drawings are substantially the same, respectively, as the front and end shown. The bottom is plain.

I claim:

The ornamental design for a box, as shown and described,
